UNITED STATES PATENT OFFICE.

SENECA G. LEWIS, OF GREENSBURG, PENNSYLVANIA.

WATCH-SUPPORT.

1,327,051.

Specification of Letters Patent.

Patented Jan. 6, 1920.

Application filed August 21, 1916, Serial No. 116,071. Renewed August 14, 1919. Serial No. 317,585.

To all whom it may concern:

Be it known that I, SENECA G. LEWIS, residing at Greensburg, in the county of Westmoreland and State of Pennsylvania, a citizen of the United States, have invented or discovered certain new and useful Improvements in Watch-Supports, of which improvements the following is a specification.

My invention relates to improvements in watch-supports, and particularly to such as are made of rubber or of material having the characteristics of rubber, and consists of a support to be used on a desk or in such like place. The object in view and advantage gained is, aside from attractiveness in appearance, the protection of the supported watch from injury, in case the support with the watch in place within it should fall from a desk or from a mantel-shelf to the floor, or sustain shock of such sort by some other contingency.

The invention is illustrated in the accompanying drawings, in which Figure 1 is a view in front elevation of a watch-support 25 of my invention; Fig. 2 is a side elevation; and Fig. 3 is a view in vertical section, on the plane indicated by the line III—III, Fig. 1.

As will be seen, the watch-support is in shape a case of familiar ornamental design, the design being that of the clock commonly known as the "ship-bell" clock.

But, by virtue of the fact that this case is formed of rubber, it possesses, aside from any matter of ornamental design, value as a watch-support which the wooden and metal clock cases of "ship-bell" pattern do not possess.

In the first place, in consequence of making the support of rubber, it may possess that feature of advantage which is characteristic of the watch-supports of my Patents Nos. 1,176,839 and 1,176,840: the feature, namely, that the support may be made all in one piece, and, by virtue of the resiliency of the material, may be stretched to receive the watch in a suitably provided pocket and may by constriction engage and securely hold the watch when brought to place in the pocket. But it possesses still other advantageous features than these.

Referring to the drawings, it will be seen that the support consists essentially of a cylindrical body 1, open through one end (through one head of the cylinder) to ex-

pose the face of an inserted watch. The opposite head of the cylinder will preferably be closed, as shown. About the periphery of the opening through the end of the cylinder is the in-turned elastic watch-retaining flange 2. Such a flanged opening is characteristic of the watch-supports of my earlier patents referred to.

But, in addition, this support of my present invention is provided, at each end of the cylindrical body with outwardly extending continuous solid flanges, 3 and 4. These flanges, by virtue of their material, their shape, and their continuity, constitute cushioning members, which, in case of a fall such as indicated above, absorb the shock and prevent injury, to the supported watch. They are indeed spring-members which, by virtue of their resiliency, cause the watch to rebound, should it fall to the floor, and so absorb the stress of the fall and protect the watch from injury. Furthermore, it will be observed of flange 3 which extends from and surrounds the open end of the cylindrical case that it flares forwardly, as well as outwardly, and so more effectually shields and guards the exposed crystal of the watch from injury.

The cylindrical case is, in service, horizontally disposed, as the drawings show; and to that end a pedestal 5 (preferably molded integrally with the rest of the support, of a single body of rubber) engages the cylindrical wall of the support. This pedestal is provided, as shown in Fig. 3, with an internal and downwardly open hollow 6. From the watch-pocket through the cylindrical wall and into this hollow 6 extends the stem-orifice 7, adapted to be enlarged to admit the passage of the winding bulb of an introduced watch and to close upon the stem when the watch comes to position. This feature is disclosed and claimed in one of my patents recited above, No. 1,176,839. It will be observed that, because the winding bulb of the introduced watch extends into the hollow 6, the bulb, while normally out of sight, is accessible for winding the watch without removal from the support, merely by picking the support up and turning it over. If an ordinary watch is used in the support, that is to say, a watch in which the dial is arranged with the character "12" adjacent to the winding stem of the watch, the dial must, in order to have it

in proper reading position, be rotated through an angle of 180° before applying it to the watch movement plate.

It will be observed too, comparing the figures of the drawing one with another, that the pedestal does not break the continuity of either of the flanges 3 and 4.

All material is, theoretically, in some degree at least, elastic; and, in the ensuing 10 claims, in order to define the novelty of my support with precision and certainty, I characterize the flange which is a feature of the support as "capable of deflection without breaking through a space greater than 15 double its thickness." This limitation certainly excludes the old wooden and metal clock-cases of "ship-bell" pattern which did not contain my present invention, and certainly includes the rubber watch-supports 20 which I am now making and which do embody my invention.

I claim as my invention:

1. A pedestal support for a watch constructed of a single piece of elastic material 25 and consisting of a foot member made of a continuous depending apron having its lower edge terminating in a horizontal plane and forming a pocket extending upwardly from said lower edge, and a vertically-dis-

posed member having formed therein a 30 watch pocket open at one side to receive and to retain a watch and to expose the face of such watch, the bottom portion of said body member being provided with a watch-stem receiving opening extending to said pocket. 35

2. A pedestal support for a watch constructed of a single piece of elastic material and consisting of a foot member made of a continuous depending apron having its lower edge terminating in a horizontal 40 plane and forming a pocket extending upwardly from said lower edge, a vertically-disposed member having formed therein a watch pocket open at one side to receive and to retain a watch and to expose the face of 45 such watch, the bottom portion of said body member being provided with a watch-stem receiving opening extending to said pocket, and a flange extending outwardly adjacent to the edge of the open face of said body 50 and encircling said edge.

In testimony whereof I have hereunto set my hand.

SENECA G. LEWIS.
